US0D1082010S

(12) **United States Design Patent** (10) **Patent No.:** **US D1,082,010 S**
(45) **Date of Patent:** **** Jul. 1, 2025**

(54) **TEETH WHITENING DEVICE**

(71) Applicant: **Nature Lab Corporation**, Aurora, CO (US)

(72) Inventor: **Wenxuan Wang**, Guangdong (CN)

(**) Term: **15 Years**

(21) Appl. No.: **29/973,448**

(22) Filed: **Nov. 15, 2024**

(51) **LOC (15) Cl.** **24-01**

(52) **U.S. Cl.**

USPC **D24/176**

Primary Examiner — Jennifer L Rempfer

Assistant Examiner — Edward P Jones

(57) **CLAIM**

The ornamental design for a teeth whitening device, as shown and described.

DESCRIPTION

FIG. 1 is a top perspective view of a teeth whitening device showing my new design.

FIG. 2 is a bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is an exploded perspective view of a teeth whitening device.

The broken lines illustrate portions of the teeth whitening device that form no part of the claimed design.

1 Claim, 9 Drawing Sheets
